UNITED STATES PATENT OFFICE.

MICHAEL D. DEADERICK, OF SEATTLE, WASHINGTON, ASSIGNOR OF ONE-HALF TO ALFRED C. ARCHER, OF SEATTLE, WASHINGTON.

DESIGN FOR A SMOKER'S STAND.

Application filed February 7, 1922. Serial No. 589. Term of patent 3½ years.

To all whom it may concern:

Be it known that I, MICHAEL D. DEADERICK, a citizen of the United States, residing at Seattle, in the county of King and State of Washington, have invented a new, original, and ornamental Design for a Smoker's Stand, of which the following is a specification, reference being had to the accompanying drawings forming a part thereof.

I claim:

The ornamental design for a smoker's stand, as shown.

Dated January 26, 1922.

MICHAEL D. DEADERICK.
